(57) **CLAIM**

The ornamental design for an adjustable dumbbells set, as shown and described.

DESCRIPTION

FIG. 1 is a front, right and top perspective view of an adjustable dumbbells set, showing my design.

FIG. 2 is a front, right and top perspective view of a handle of the adjustable dumbbells set in FIG. 1.

FIG. 3 is a rear, left and bottom perspective view of the handle of FIG. 2.

FIG. 4 is a front elevation view of the handle of FIG. 2.

FIG. 5 is a rear elevation view of the handle of FIG. 2.

FIG. 6 is a left side elevation view of the handle of FIG. 2.

FIG. 7 is a right side elevation view of the handle of FIG. 2.

FIG. 8 is a top plan view of the handle of FIG. 2.

FIG. 9 is a bottom plan view of the handle of FIG. 2.

FIG. 10 is a front, right and top perspective view of a dumbbell of the adjustable dumbbells set in FIG. 1.

FIG. 11 is a rear, left and bottom perspective view of the dumbbell of FIG. 10.

FIG. 12 is a front elevation view of the dumbbell of FIG. 10.

FIG. 13 is a rear elevation view of the dumbbell of FIG. 10.

FIG. 14 is a left side elevation view of the dumbbell of FIG. 10.

FIG. 15 is a right side elevation view of the dumbbell of FIG. 10.

FIG. 16 is a top plan view of the dumbbell of FIG. 10.

FIG. 17 is a bottom plan view of the dumbbell of FIG. 10.

FIG. 18 is an enlarged view of detail 18 in FIG. 10; and,

FIG. 19 is an enlarged view of detail 19 in FIG. 10.

The broken lines depict portions of the adjustable dumbbells set that form no part of the claimed design. The dot-dash broken lines in FIGS. 10, 18, and 19 depict the boundaries of the enlargements that form no part of the claimed design.

1 Claim, 19 Drawing Sheets
